TUBE CLOSURE VALVE

Orton B. Stauffer, Berea, Ohio

Application March 4, 1932, Serial No. 596,858

8 Claims. (Cl. 221—60)

In accordance with the provisions of what has heretofore been considered the usual practice, collapsible tubes are provided with a removable cap adapted to be threaded over the nipple forming the outlet for material contained in the tube. These separable caps are often the source of considerable inconvenience through the tendency thereof to become lost or mislaid while the tube contents are being used, and also because of accidental deformation of the caps through dropping the same, so that there is a rather substantial likelihood of accidental deformation of these caps so that they can no longer readily be inserted upon or removed from the tube.

The present invention is designed to supply a means for eliminating the use of such removable caps, and provides a closure member or valve fixedly secured in position so as to control the outlet passage through the nipple. By making this valve inseparably mounted in the tube construction, all inconvenience resulting from loss of the closure member for the tube is eliminated, and there is provided, through a very simple construction, a device which is always in place and which will serve to effectively retain the contents of the tube, preventing any further discharge of the tube when the desired supply of material is discharged therefrom. It may be mentioned in passing that in the type of tube provided with the screw cap closure, it is sometimes difficult to stop the contents of the tube from continuing to ooze through the discharge opening, especially when the contents are of a semi-liquid consistency.

The invention will be more readily understood by reference to the accompanying drawing, in which

Figure 1 shows a side view of a collapsible tube provided with the improved closure valve.

Figure 2 is a detail view of the discharge end of the tube showing the provision of securing and sealing means for the closure valve and outlet of the tube, whereby a purchaser of the tube may know by inspection that the tube is in good condition, with its contents fully protected until ready to be used.

Figure 3 is a sectional view through the nipple of the tube, showing certain details of the closure valve, the view being taken on the line 3—3 of Figure 2.

Figure 4 is a sectional view along the line 4—4 of Figure 3 and showing further details of the construction of the closure valve.

Figure 5 is an end view, showing in dotted lines the position of the closure valve, the securing arm being omitted.

Figure 6 is a fragmentary side elevation of the discharge end of the tube, showing certain other details of the closure valve, the operating handle being broken off, the view being taken along the line 6—6 of Figure 4.

Figure 7 is a perspective view of a retaining collar employed in connection with the closure valve.

Referring more particularly to the drawing, a collapsible tube is indicated generally at A, and is provided with the discharge nipple B, in accordance with the usual practice, which has extending therethrough the passage 1 to allow the escape of the contents of the tube as desired. In this passage is located the closure valve of the present invention, and is shown as being formed of the valve body 2 provided with an opening 3, which is adapted to register with the passage 1 of the nipple B, it being understood that the nipple B is suitably recessed for the admission of the body 2, which snugly, but turnably, fits therein. Secured to the body 2 is an operating handle 4, which may be made integral with the body 2 or secured removably therewith in any desired manner. To secure the body 2 in position there is provided the retaining collar or washer 5 which is provided with the open slot 6 to receive a stem 7 on the operating handle 4. The collar or washer 5 is removably secured in position by pressing around it the walls of the opening 8 in which the body 2 is received, thus causing the sides of the slot 6 to firmly grip the stem 7 in the handle 4. The gripping engagement between the walls of the aperture and the periphery of the washer firmly secures the washer in place and effectively prevents displacement of the valve body 2 on its seat in the recess 8.

To safeguard the handle 4 from accidental movement and to serve as a protection to the consumer, there may be provided a frangible securing element or arm 9 so arranged that the handle 4 cannot be turned without breaking the securing element. The discharge aperture 1 may also be provided with a frangible sealing member 10 so that the contents of the tube may be doubly protected, as they cannot be discharged without breaking both elements 9 and 10.

The operating handle 4 is desirably positioned so that the wings thereof will engage the shoulder 11 of the tube in such a manner that when the bore 3 is in full registry with the passage 1, the handle 4 will be in engagement with the shoulder 11 in full open position and cannot be further turned in the same direction; and similarly when the bore 3 is brought fully out of registry with the discharge passage 1, the other side of the handle 4 will engage the shoulder 11, so that the outlet will be completely closed and there is no possibility of overturning the valve body 2 in either direction of its operation.

To improve the appearance of the article, the handle 4 may be made in any suitable color, as desired.

It will be seen that a quarter turn of the handle 4 in the direction of the arrow in Figure 3

- will serve to bring the bore 3 into exact registry with the passage 1, and the handle will be in engagement with the shoulder 11. A suitable turn in the reverse direction brings the valve into closed position as shown in Figure 3. To assure proper breakage of the frangible arm 9 it may be provided with a suitable dividing line 9a along which the fracture will occur when the handle 9 is turned.
- Having thus described my invention, what I claim as new and desire to secure by Letters Patent of the United States, is—
1. A device of the character described, comprising a discharge member provided with a passageway for the discharge of materials therethrough, and provided with a valve receiving recess, a valve unit mounted in the recess comprising a body member having a bore extending therethrough and an operating handle for turning the body in the said recess, and a retaining collar fixedly mounted in said recess and gripping the said unit to prevent displacement of the body from the recess while allowing free turning thereof to bring the said bore into and out of registry with the discharge passageway for controlling the discharge of materials through the said passageway.
  2. A collapsible tube provided with a discharge nipple having a passageway therethrough for discharge of materials contained in the tube, and a closure valve mounted in the said passageway for opening and closing the same and comprising a valve body seated within the nipple and adapted to freely turn therein, the said body having a bore extending therethrough adapted to be brought into and out of registry with the discharge passageway through the nipple, an operating handle for the body member, and a retaining collar inseparably secured in the nipple against the said valve body member, to prevent accidental displacement of the latter from its seated position in the nipple.
  3. A construction of the character described, comprising a collapsible tube having a discharge nipple and defining a shoulder therewith in the upper zone, the said nipple being provided with a discharge passageway therethrough, and a closure valve for the passageway located within the nipple, comprising a valve body having a bore extending therethrough adapted to be brought into and out of registry with the passageway through the nipple, an actuating handle for the body member being provided with means adapted to engage with the said shoulder of the tube around the nipple to prevent over-passage of the bore relatively to the passageway through the nipple to assure proper engagement and disengagement between the bore and passageway for opening and closing the tube, and means interposed intermediate the valve body and the surface of the discharge nipple securing the body member against accidental displacement in the nipple.
  4. A construction of the character described comprising a collapsible tube provided with a nipple having a discharge passageway therethrough, a closure valve positioned in the nipple and comprising a valve body member having a bore therethrough adapted to be brought into and out of registry with the discharge passageway through the nipple, operating means for turning the valve

body member for controlling the discharge passageway, and a frangible securing member connected with the operating means to prevent turning thereof prior to the initial use of the construction in any direction.

5. A construction of the character described, comprising a collapsible tube provided with a nipple having a discharge passageway therethrough, a closure valve positioned in the nipple and comprising a valve body member having a bore therethrough adapted to be brought into and out of registry with the discharge passageway through the nipple, operating means for turning the valve body member for controlling the discharge passageway, a frangible securing arm formed as a part of the operating means for turning the valve body member acting as a guard through engagement with the collapsible tube to prevent turning of the valve body member prior to the initial use of the construction, and a frangible sealing member positioned in the discharge passageway of the nipple.

6. A closure valve construction for collapsible tubes and the like and adapted to be inserted in the usual nipple of the tube, the said nipple being suitably recessed partially therethrough to provide a valve seat internally thereof and having the usual discharge passage therethrough, comprising a valve body member having a bore therethrough, and snugly but turnably fitting in the nipple recess with the said bore registering with the discharge passage through the nipple, an operating handle integral with the valve body for turning thereof, and a retaining collar fixedly mounted in the nipple recess in engagement with the valve body to secure the latter permanently in the recess.

7. In combination, a collapsible container having a discharge opening and a valve for controlling the discharge of the contents of the tube through said discharge opening, which includes a neck on said container having a bore therein at right angles to the discharge opening, a valve body located in said bore, a passage in said valve body for registry with the discharge opening, a handle for rotating said valve body having a part integral with said valve body, means lying intermediate said part and the wall of said bore and being retained therein against axial travel for preventing axial travel of the valve body.

8. In combination, a container having a discharge neck and a discharge orifice therein, and a valve for controlling the passage of contents within said container through the discharge opening, said neck having a bore therein closed at one end for receiving the valve, said valve including a valve body having a passage therein for registry with the discharge opening and communicating with the interior of the container, means for rotating said valve, means for limiting the axial travel of the valve body to maintain proper alignment between the passage in said valve body and the discharge opening when said valve body is rotated to bring said parts into alignment, and means for rotating said valve body comprising a handle, and means for preventing the rotation of said handle prior to the initial use of the construction.

ORTON B. STAUFFER.
